FIG. 1

FIG. 2

FIG. 3

FIG. 4

FIG. 5

FIG. 6

FIG. 7

FIG. 1 is a front elevational view of a radio, showing one form of my new design;

FIG. 2 is a right side elevational view of the form shown in FIG. 1;

FIG. 3 is a left side elevational view of the form shown in FIG. 1;

FIG. 4 is a top plan view of the form shown in FIG. 1;

FIG. 5 is a bottom plan view of the form shown in FIG. 1;

FIG. 6 is a rear elevational view of the form shown in FIG. 1; and

FIG. 7 is a rear elevational view of a radio, showing another form of my new design, the front, right side, left side, top and bottom having substantially the same appearance as in FIGS. 1, 2, 3, 4, 5 respectively.

Portions of the drawing figures are diagonally lined to indicate transparency, and portions are shaded to indicate contrast in appearance. The dash-dash lines indicate stitching.

I claim:

The ornamental design for a radio, as shown and described.
